(57) **CLAIM**

The ornamental design for an air fryer as shown and described.

DESCRIPTION

FIG. 1 is a front, right and top perspective view of an air fryer, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of a second embodiment of an air fryer.

FIG. 10 is a rear, right and bottom perspective view of the second embodiment of the air fryer of FIG. 9.

FIG. 11 is a front elevation view of the second embodiment of the air fryer of FIG. 9.

FIG. 12 is a rear elevation view of the second embodiment of the air fryer of FIG. 9.

FIG. 13 is a left side elevation view of the second embodiment of the air fryer of FIG. 9.

FIG. 14 is a right side elevation view of the second embodiment of the air fryer of FIG. 9.

FIG. 15 is a top plan elevation view of the second embodiment of the air fryer of FIG. 9; and,

FIG. 16 is a bottom plan elevation view of the second embodiment of the air fryer of FIG. 9.

The broken lines depict portions of the air fryer that form no part of the claimed design.

1 Claim, 16 Drawing Sheets
